(57) **CLAIM**

I claim the ornamental design for a wall sconce light fixture, as shown and described.

DESCRIPTION

FIG. 1 shows a perspective view of a wall sconce light fixture.

FIG. 2 shows a front elevation view of the wall sconce light fixture.

FIG. 3 shows a right side elevation view of the wall sconce light fixture, the left side view being a mirror image thereof.

FIG. 4 is a top plan view of the wall sconce light fixture.

FIG. 5 is a back elevation view of a wall sconce light fixture; and,

FIG. 6 is a bottom view of a wall sconce light fixture.

The broken lines shown on the drawings are for illustrative purposes only and form no part of the claimed design.
